BELT BUCKLE

Herbert J. Buchsbaum, Chicago, Ill., assignor to
 A. Stein & Company, Chicago, Ill., a corpora-
 tion of Illinois

Application May 31, 1939, Serial No. 276,502

5 Claims. (Cl. 24—191)

This invention relates to improvements in belt buckles and more specifically to improvements in belt buckles such as used on waist belts of leather or other materials, and of the type which are 5 adapted to grip the belt at any selected location without penetrating the same.

The main objects of the invention are to provide a buckle of the type indicated which will grip belts effectively notwithstanding considerable variation in the thickness of the belts so that 10 a single buckle construction may be used for belts of a wide range of thicknesses; to provide a buckle structure of the character indicated which, although unusually effective, is nevertheless of simple construction and easy and inexpensive to make so as to be commercially practicable; to provide a buckle of the character indicated which will be durable and easy to operate and which will not injure the belt; and in general, it is the object of the invention to provide 15 an improved buckle of the type set forth.

Other objects and advantages of the invention will be understood by reference to the following specification and accompanying drawings, wherein the improved buckle is illustrated.

In the drawing:

Figure 1 is an elevation of the inside of the buckle associated with a leather belt;

Figures 2 and 3 are sections, respectively, on 30 the lines 2—2 and 3—3 of Figure 1; and

Figure 4 is a perspective illustrating one of the parts of the improved buckle.

Referring now to the drawing, the improved buckle comprises a sheet metal outer buckle member 5 stamped or otherwise formed to provide a front plate part 6, top and bottom flanges 7 and 8, respectively, and inwardly extending rear flanges 9 and 10. The rear flanges 9 and 10, respectively, are further provided with end 40 portions folded or rolled to provide bearings 11 and 12 for receiving trunnions 13 and 14, respectively, of a gripper member 15.

The gripper member 15 is made in one piece of suitable sheet metal and it is stamped or otherwise fabricated to provide the illustrated frame-like structure comprising a belt-attaching cross-bar 16, side arms 17 and 18 extending edgewise from said cross-bar, belt gripper bars 19 and 20 connected at their ends to the inner edges of 50 said side arms, and said trunnions 13 and 14.

The gripper bars are laterally offset from the normal plane of the cross-bar 16 and arms 17 and 18. The said bars 19 and 20 are laterally offset toward the buckle face 5 and they are 55 preferably, but not necessarily, pressed to the longitudinally arched formation shown.

The said gripper bars 19 and 20 are spaced apart a distance approximately equalling the thickness of the metal from which the member 60 is formed and the bar 20 is offset from the plane

of the arms 17 and 18 to a slightly greater extent than the bar 19. The said gripper bars are also bent forwardly to an inclined position relative to the normal plane of the gripper (the plane of the cross-bar 16 and arms 17 and 18) 5 which causes outer corners 22 and 21 of the bars 19 and 20, respectively, to bite into the belt fabric whether of leather or other material, thereby to effectively grip the buckle in cooperation with 10 the buckle member 5.

The bar 20 is further so arranged that its highest edge 21 is located only slightly forwardly of the axis of the trunnions 13 and 14. The bar 19 is so located that its highest point 22 is located considerably rearwardly of the axis of said 15 trunnions.

The buckle is attached to one end of a belt by having such end of the belt passed around the transverse bar 16 of the gripper 15, bent back and permanently or detachably secured to 20 the belt, or it may be secured in any other suitable or conventional way. In Figures 1 and 2, a belt 23 is shown as having an end portion 24 thereof folded around the bar 16 and detachably secured to the belt by means of a snap fastener 25. The other end portion 26 of the belt is inserted 25 between the inside face of the buckle part 5 and the adjacent outer faces of the gripper bars 19 and 20, such insertion being freely permitted 30 by rocking the gripper member 15 outwardly on its trunnions 13 and 14 so as to rock the bars 19 and 20 rearwardly from the buckle part 5.

When the belt strap 26 has been passed through the buckle to the desired extent, the gripper 15 is restored to normal gripping position as shown 35 in Figure 2, whereupon the bars 19 and 20 engage the belt strap so as to pinch it against the inside of the buckle part 5. The bar 19 has the effect of causing the belt strap to swell or bulge between the bars whereby the gripping effect of the 40 bar 20 is increased. Because of the offset relationship of the front bar 19 to the pivotal axis of the gripper member 15, the said bar 19 will prevent the gripper member from rocking on 45 its pivot (when the belt is under strain) to such an extent that the other bar 20 will begin to release the strap.

The front gripping bar 20 will normally be embedded in the belt strap to a less extent than 50 the rear gripping bar 19, especially in connection with a relatively thick belt strap. Because of the angular disposition of the bars 19 and 20, each of them will be caused to so enter and engage the belt that the belt is held by the relatively abrupt edge faces 27 and 28 of the respective bars 19 and 20. The angular position of the outer face 29 of the bar 19 is such that it tends to swage the material of the belt into a 55 swell adjacent the abrupt face 28 of the bar 20 60

with consequent increase in the holding effect of the latter.

The gripper member 15 is preferably formed of sheet metal having a substantial degree of resiliency but which is nevertheless strong enough to withstand the stresses imposed on the gripper member incident to its employment as above explained. One suitable metal for this purpose is half-hard brass about one-sixteenth of an inch in thickness; the employment of a resilient metal such as referred to is desirable, although not essential, in that it provides a certain amount of "give" in the gripper structure in its entirety, and especially in the gripping bars 19 and 20. Such resiliency may permit the bar 20 to be sprung to a position of increased or decreased angularity and to a less arched position when extremely thick belts are encountered. Furthermore, the absence of any rigid connection between the arms 17 and 18 of the gripper member, at the ends thereof remote from the belt-attaching bar 16, permits the said arms to spread so as to accommodate the expansive pressure of the pinch bars 19 and 20 when under belt-gripping pressure. Such "give" in the gripper element enables the buckle to be used, without special adjustment, interchangeably on belts of different thicknesses and it also permits the gripping bars to follow the pull of the belt when under strain so as to increase the gripping power as the strain is increased. The buckle member 5, being of sheet metal construction, is also capable of yielding slightly when the grippers 19 and 20 apply sufficient force against the buckle through the gripped portion of a belt strap.

The gripper member as described is highly effective for its purpose but it may be modified to have three or more bars instead of two as shown, and other changes in the described construction may be made without departing from the principles of the invention, the scope of which should be determined by reference to the following claims, the same being construed as broadly as possible, consistent with the state of the art.

I claim:

1. A belt buckle of the class described comprising a front member and a gripper member pivotally connected to said front member, said gripper member having a belt-attaching bar, side arms extending laterally from the ends of said attaching bar, and a pinch bar spaced from said attaching bar and extending between and connected at its ends to said side arms, said pinch bar being arched toward said front member from the plane of the portions of the side arms to which the pinch bar is connected, said arched pinch bar being adapted to be flexed toward said plane when under belt-gripping pressure and said side arms being adapted to be spread laterally as an incident to such flexing of the pinch bar.

2. A belt buckle of the class described comprising a front member and a gripper member pivotally connected to said front member, said gripper member having a belt-attaching bar, side arms extending laterally from the ends of said attaching bar, and a pinch bar of generally rectangular cross-section, spaced from said attaching bar and extending between and connected at its ends to said side arms, said pinch bar being arched toward said front member from the plane of the portions of the side arms to which the pinch bar is connected and having its face and the edge thereof adjacent said attaching bar disposed at an acute angle relative

to the normal plane of said front member when the gripper is in gripping relation to the front member, whereby the longitudinally extending corner formed by said face and edge of the pinch bar is adapted to bite into a strap interposed between said front member and gripper.

3. A belt buckle of the class described comprising a front member and a gripper member pivotally connected to said front member, said gripper member having a belt-attaching bar, side arms extending laterally from the ends of said attaching bar, and a pair of pinch bars spaced from each other and from said attaching bar and extending between and connected at their ends to said side arms, said pinch bars being arched toward said front member from the plane of the portions of the side arms to which the pinch bars are connected, said arched pinch bars being adapted to be flexed toward said plane when under belt-gripping pressure and said side arms being adapted to be spread laterally as an incident to such flexing of the pinch bars.

4. A belt buckle of the class described comprising a front member and a gripper member pivotally connected to said front member, said gripper member having a belt-attaching bar, side arms extending laterally from the ends of said attaching bar, and a pair of pinch bars of generally rectangular cross-section, spaced from each other and from said attaching bar and extending between and connected at their ends to said side arms, said pinch bars being arched toward said front member from the plane of the portions of the side arms to which said pinch bars are connected and having their faces and the respective edges thereof adjacent said attaching bar disposed at an acute angle relative to the normal plane of said front member when the gripper is in gripping position, whereby the corners formed by the faces and edges of the pinch bars are adapted to bite into a strap interposed between said front member and gripper, the pinch bar nearest said belt-attaching bar having its face disposed in a plane which, if extended, would underlie the plane of the face of the other pinch bar.

5. A belt buckle of the class described comprising a front member and a gripper member pivotally connected to said front member, said gripper member having a belt-attaching bar, side arms extending laterally from the ends of said attaching bar, and a pair of pinch bars of generally rectangular cross-section, spaced from each other and from said attaching bar and extending between and connected at their ends to said side arms, said pinch bars being arched toward said front member from the plane of the portions of the side arms to which said pinch bars are connected and having their faces and the respective edges thereof adjacent said attaching bar disposed at an acute angle relative to the normal plane of said front member when the gripper is in gripping position, whereby the corners formed by the faces and edges of the pinch bars are adapted to bite into a strap interposed between said front member and gripper, the pinch bar nearest said belt-attaching bar having its face disposed in a plane which, if extended, would underlie the plane of the face of the other pinch bar.
